UNITED STATES PATENT OFFICE.

CHARLES T. WESTLAKE, OF ST. LOUIS, MISSOURI, ASSIGNOR TO COMMONWEALTH STEEL COMPANY, OF ST. LOUIS, MISSOURI, A CORPORATION OF NEW JERSEY.

PILOT-BEAM.

1,127,331.

Specification of Letters Patent. Patented Feb. 2, 1915.

Application filed July 17, 1914. Serial No. 851,488.

To all whom it may concern:

Be it known that I, CHARLES T. WESTLAKE, a citizen of the United States, residing at St. Louis, Missouri, have invented a certain new and useful Improvement in Pilot-Beams, of which the following is a full, clear, and exact description, such as will enable others skilled in the art to which it appertains to make and use the same, reference being had to the accompanying drawings, forming part of this specification, in which—

Figure 1 is a front elevational view of a pilot beam of my improved construction. Fig. 2 is an end elevational view of the beam. Fig. 3 is a front elevational view of the end portion of a modified form of the beam. Fig. 4 is an end elevation of the form of beam seen in Fig. 3. Fig. 5 is a front elevational view of the end portion of a further modified form of the beam. Fig. 6 is an end elevation of the form of beam illustrated in Fig. 5. Fig. 7 is a front elevational view of the end portion of a further modified form of the beam. Fig. 8 is an end elevation of the form of beam illustrated in Fig. 7. Fig. 9 is a front elevational view of the end portion of a further modified form of the beam. Fig. 10 is an end elevation of the form of beam illustrated in Fig. 9. Fig. 11 is a front elevational view of the end portion of a further modified form of the beam. Fig. 12 is an end elevation of the form of beam illustrated in Fig. 11.

My invention relates to pilot beams for locomotives, the principal object of my invention being to construct the end portions of a pilot beam so as to prevent the application of jack screws to said end portions during the raising of the locomotive to which the beam is applied.

Pilot beams of ordinary construction have flat lower faces at their ends and when it becomes necessary to elevate the locomotive, repair-men find the flat underfaces at the ends of the pilot beam convenient points to locate the blocks for jack screws. Such procedure renders the pilot beam easily susceptible to breakage for the reason that the application of lifting power at the outer end of the beam produces much higher stresses than are ordinarily developed in service. Consequently, it is desirable to provide a structure which will prevent the jack screws

from being placed beneath the outer ends of the beams, and compel their application nearer the center of the pilot beam and the center of the locomotive.

With the foregoing and other objects in view, my invention consists in certain novel features of construction, hereinafter more fully described and claimed.

In the construction illustrated in Figs. 1 and 2, the end portions of the beam 1 are formed of less depth than the central portion of the beam, and said end portions are provided with transversely curved lower faces 2. The inner ends of these curved faces curve inwardly and downwardly as designated by 3 until they meet the flat underface 4 of the central portion of the beam. If desired, portions of the flat lower face 4 may be roughened or corrugated as designated by 4^a, said roughened or corrugated faces serving as seats or bearing points for the upper ends of the jack screws, when same are used. By such construction the curved faces 2 can not conveniently be used as seats or bearing faces for the blocks at the upper ends of jack screws, and consequently, when said jack screws are used, they must be applied to the end portions of the flat lower face 4 and consequently, said jack screws are located at points adjacent to the center of the beam and the locomotive, where they will be effective in lifting the locomotive without liability of bending or breaking said beam.

In the construction illustrated in Figs. 3 and 4, the lower corner at the outer end of each beam is cut away to form a longitudinally disposed inclined face 5.

In the construction illustrated in Figs. 5 and 6, the lower corner at each end of the beam is cut away so as to form a longitudinally disposed inclined face 6, the same being convexedly curved in cross section.

In the construction illustrated in Figs. 7 and 8, the lower corner at each end of the beam is cut away to form a longitudinally disposed face 7 which curves gradually upward from the lower flat face 4 to the outer end face 8 of the beam.

In the construction illustrated in Figs. 9 and 10, the lower corner at each end of the beam is provided with a longitudinally disposed curved face 9, which is convexedly curved in transverse section.

In the construction illustrated in Figs. 11

and 12, the underside of the beam at each end is made V-shape in cross section so as to provide a pair of oppositely disposed inclined faces 10. Formed on the front face of the beam near the ends are the usual push pole pockets 11.

Pilot beams of my improved construction effectually preclude the application of lifting jacks and like devices at points beneath their ends, and consequently when it becomes necessary to use jacks in lifting a locomotive equipped with the improved beam, said jacks must be applied beneath the beam at points near the center thereof, consequently eliminating the danger of bending or breaking the beam during the lifting operations.

I do not desire to limit myself to the exact details herein shown and described, as the

end portions of the beam may vary in form, without departing from the spirit of my invention, the scope of which is set forth in the appended claim.

I claim:

A pilot beam having irregular underfaces near its ends such that jack lifting power is not applicable thereto, and provided with jacking surfaces located only at points remote from its ends.

In testimony whereof I hereunto affix my signature in the presence of no witnesses, this 25th day of June, 1914.

CHARLES T. WESTLAKE.
